DESIGN FOR A DESK STAND

Maurice Ress, New York, N. Y.

Application January 29, 1948, Serial No. 144,131

Term of patent 7 years

(Cl. D48—20)

To all whom it may concern:

Be it known that I, Maurice Ress, a citizen of the United States of America, and a resident of the city of New York, county of Kings and State of New York, have invented a new, original, and ornamental Design for a Desk Stand, of which the following is a specification; reference being had to the accompanying drawings, forming a part thereof. The essential features of the design reside in the portions shown in solid black lines.

In the drawings:

Fig. 1 is a front elevational view of a desk stand, showing my design;

Fig. 2 is a view taken on line 2—2 of Fig. 1;

Fig. 3 is a rear elevational view of the same; and

Fig. 4 is a side elevational view of the same, as seen from the right side of Fig. 1.

I claim:

The ornamental design for a desk stand, substantially as shown and described.

MAURICE RESS.
